DESIGN FOR A BLOUSE

Mark Knebel, New York, N. Y.

Application December 28, 1940, Serial No. 97,684

Term of patent 3½ years

To all whom it may concern:

Be it known that I, Mark Knebel, a citizen of the United States, residing at New York city, in the county of New York and State of New York, have invented a new, original, and ornamental Design for a Blouse, of which the following is a specification, reference being had to the accompanying drawing, forming part thereof.

In the drawing:

Fig. 1 is a front view of a blouse showing my new design; the rear of said blouse being of conventional design.

Fig. 2 is another front view of the said blouse, with the pleats formed on the sleeves and body of the blouse in extended position.

I claim:

The ornamental design for a blouse, as shown.

MARK KNEBEL.
